BURIAL URN

William A. Prier, Portland, Oreg.

Application March 10, 1933. Serial No. 660,253

3 Claims. (Cl. 27—1)

Conforming to modern practice which dispenses with the old monument and headstone and having in mind the increasing tendency to make use of cremation, I have designed my 5 burial urn with the following objects in view.

To provide a receptacle for ashes of cremation that will combine with it a grave marker without in any way being distinguishable by superficial inspection from the bronze marker 10 now so commonly in use.

To construct a receptacle of the character indicated wherein the ashes of cremation may be deposited and the whole sealed in a block of cement concrete or the like whereby the act of 15 sealing into the concrete hermetically seals the receptacle itself.

With these and other objects in view I have made my invention of which that shown in the accompanying drawing is a preferred form, in 20 which,

Fig. I is a plan view as it will appear when placed in a cemetery;

Fig. II is a transverse section on the line II—II of Fig. I; and

Fig. III is a transverse section on the line III—III of Fig. II.

The burial urn is preferably made of high grade bronze cast in one piece except the closure member hereinafter described, and is made individually for each grave with the name cast in 30 one piece with the cover portion, 4, which will be provided with a suitable ornamental border, 5, and the general surface, 6, should be stippled or otherwise executed in an artistic manner, the 35 surface of the lettering being buffed.

The sides, 7, and the ends, 8, are shown to be slanted outwardly so that the bottom, 9, is larger than the top, 4; thus, when imbedded in a concrete block such as 10, withdrawal of the bronze 40 receptacle will be impossible without destruction of the concrete. Thus is vandalism impeded.

An opening, 11, is provided with a closure, 12, preferably screw threaded therein and the threads should be made tapering or other provision made 45 to positively exclude moisture and no gaskets of soft material that is perishable should be used.

It is obvious that instead of making the bottom larger than the top that irregularities of various kinds may be arranged on the body of the receptacle so that it cannot be withdrawn from the concrete. I therefore do not wish to make this particular feature an essential, though it is an excellent way of attaining the desired result. 55

The material for the concrete block, 8, should be of high grade Portland cement and proper aggregates to make an exceedingly strong hard block and when this is done and considering the resistance of high grade bronze it will be seen 60 that a degree of permanency is present in the whole structure that is not even approached by a building or even underground vault within which to store urns and receptacles of this character; that its sanitary qualities are unsurpassed 65 and will be very difficult to improve upon and its aesthetic value will be apparent at once. High grade bronze, as has been proved by bronze structures of ancient centuries, is not subject to atmospheric attrition; and cement concrete, 70 though younger, is agreed by scientists to be permanent in this regard.

Having thus described my new invention so that anyone familiar with the art to which it appertains can make and use the same, what I 75 claim as new and desire to secure by Letters Patent, is—

1. An urn for the permanent care of ashes of incineration defined as a metallic frusto-pyramidal receptacle of cast metal, memorial indicia 80 cast integral with the top, a hollow interior to form a receptacle for the ashes, a closure for hermetically sealing the interior and a concrete monolith molded around said metallic receptacle, exposing the top of the receptacle substantially 85 flush with one surface of the monolith.

2. An urn for the permanent care of ashes of incineration defined as a concrete monolith provided with a substantially flat surface, a metallic receptacle imbedded in the said monolith 90 with one surface thereof substantially flush with the monolith, memorial indicia formed integral with the exposed surface of the receptacle, metallic means for hermetically sealing the receptacle before placing in the monolith, said sealing 95 means being imbedded below the surface of the monolith after insertion.

3. An urn for ashes of incineration comprising a memorial plate portion and a receptacle portion integral therewith, an opening for the receptacle portion and a closure for hermetically sealing the same, external outlines for said urn adapted to anchor the urn when moulded in a block of concrete, leaving the memorial exposed and the closure covered. 100
